UNITED STATES PATENT OFFICE.

THOMAS MORGAN, OF WORCESTER, MASSACHUSETTS, ASSIGNOR TO
CLARENCE W. HOBBS, OF SAME PLACE.

METHOD OF APPLYING STAY-STRIPS TO BOXES.

SPECIFICATION forming part of Letters Patent No. 663,037, dated December 4, 1900.

Application filed November 11, 1898. Serial No. 696,128. (No model.)

To all whom it may concern:

Be it known that I, THOMAS MORGAN, a citizen of the United States, and a resident of Worcester, in the county of Worcester and State of Massachusetts, have invented certain new and useful Improvements in Methods of Applying Stay-Strips to the Corners of Boxes, of which the following is a specification.

In the manufacture of paper boxes it is customary to apply to the outside of the box-corners narrow strips of strong paper or muslin, which are securely pasted to the outside of the box-corners in order to reinforce or strengthen the corners of the box, and for additional security the end of the stay-piece is sometimes turned over the edge of the box and pasted on the inside of the box-corner, thereby securely uniting the adjacent sides of the box-body, which is then covered upon its outer surface with a covering-strip of paper. The stay-strips are applied at a distinct operation either by hand when the strips are caused to adhere to the box-body by being rubbed into close contact therewith by the hand of the operator or by a corner-staying machine by which a narrow adhesive stay-strip is applied to the corner of the box and pressed between two dies having annular faces. When the stay-strip is applied by hand, the air is expelled from between the stay-strip and the box-body and the stay-strip is brought into close contact with the surface of the box, notwithstanding the irregularities of its surface, as the pressure of the hand accommodates itself to any unevenness in the surface of the box-body, and a stay-strip of flexible material can be used, such as thin paper or cloth, which conforms readily to the surface of the box and dries without peeling.

In the case of a machine-applied stay-strip a material of considerable stiffness must be used capable of being controlled by the operation of the machine, and a heavy pressure must be applied by the compressing-dies in order to overcome any unevenness in the surface of the box, and the adhesion of a machine-applied strip is usually imperfect as compared with that of a hand-applied stay-strip, owing to the imperfect contact secured by the pressure of the dies and to the tend-

ency of a heavy or stiff stay-strip to peel off in the process of drying.

My present invention relates to a new and improved method of applying the stay-strips to the corners of paper boxes by which the stay-strips and the covering-strip are both applied to the box at a single operation, and the adhesion of the stay-strip to the surface of the box is secured by its being rubbed by the hand of the operator, as in the case of a hand-applied stay-strip, thereby expelling the air between the stay-strip and the surface of the box and securing a perfect adhesion of the stay-strip; and it consists in attaching the stay-strips to the under side of a covering-strip at proper intervals corresponding with the distances between the corners of the box, so that as the covering-strip is applied in the usual manner to the box the stay-strips will be carried along with the covering-strip and applied to the corners of the box. The under side of the stay-strips and covering-strip are rendered adhesive and are rubbed against the surface of the box by the hand of the operator as the covering-strip is wound thereon. My present invention, however, does not relate to any especial means for attaching the stay-strips to a covering-strip, but it consists, broadly, in the method of applying a stay-strip to the box-corner during the operation of covering a box with a strip of covering-paper by attaching the stay-strips to the under side of the covering-strip with the under side of the stay-strip rendered adhesive, so that in the application of the covering-strip to the box-body by any of the ordinarily-practiced methods a stay-strip will be carried along with the covering-strip and applied to the corners of the box and rubbed into adhesive contact with the box simultaneously with the application of the covering-strip.

In the accompanying drawings, which illustrate my improved method of applying stay-strips to the corners of paper boxes, Figure 1 represents a side elevation of a box-covering machine now in common use for applying a covering-strip of paper to the outside of the box. Fig. 2 is a plan view of the same. Fig. 3 represents the under side of a portion of a covering-strip, showing stay-strips at-

tached thereto; and Fig. 4 represents in perspective view a paper box having the corner stay-strips and covering-strip applied to the outside of the box by the operation of a 5 covering-machine, as shown in Figs. 1 and 2, preparatory to turning the covering-strip and stay-strips over the edge of the box and attaching them to its inner side.

Similar characters refer to similar parts in 10 the different figures.

Referring to the drawings, 1 denotes the framework of a covering-machine; 2, the rotating box-form; 3, a cutting mechanism by 15 which the covering-strip is severed; 4, a gumming-roll partially immersed in adhesive material contained in a gum-box or paste-pan 5 and running in contact with the continuous covering-strip 6, which is taken from a coil 7, supported upon a rotating spool or reel 8 20 and conducted over the gum-roll 4 and supporting-rods 9 between the cutting mechanism 3 to the rotating box-form 2, where it is applied by the operator to a paper box 10 supported upon the box-form.

25 The construction and operation of the above-described mechanism for applying a covering-strip to a paper box will be well understood by those conversant with the manufacture of paper boxes, as covering-machines 30 of the type illustrated in the accompanying drawings are well known and in common use in the manufacture of paper boxes.

In carrying my invention into practice I first attach to the under side of a covering-strip 35 adapted to be applied to a paper box a series of stay-strips arranged at stated intervals corresponding to the distances between the corners of the box to be covered, so that when the covering-strip is wound in the usual manner upon the box the stay-strips will register accurately with and be applied in the proper position to the corners of the box and rubbed into adhesive contact therewith by the hand of the operator simultaneously with the application of the covering-strip.

45 In Fig. 3 I have represented the under side of a covering-strip with a series of stay-strips attached thereto and at predetermined distances apart corresponding with the sides of 50 the box to be covered, so that in the operation of applying the covering-strip the stay-strip *a* will be applied to the corner *A* of the box, and as the covering-strip is wound around the box by the rotation of the box-form in the direction of the arrow 11 stay-strip *b* will register with and become applied to the corner *B*, stay-strip *c* to the corner *C*, and stay-strip *d* to the corner *D* of the box. 55 Between the stay-strip *d* and the next succeeding stay-strip *a'* a space is left slightly longer than the side of the box between its

corners *D* and *A*, so that the covering-strip between the stay-strip *d* and the broken line 12 will cover the side of the box and leave a small portion 13 of the covering-strip to be 65 attached to the next succeeding box, thereby forming a lap in the covering-strip.

In the arrangement of the stay-strips upon the under side of the covering-strip the spaces between the stay-strips will successively 70 equal the length of the box sides 14, 15, and 16, and the side 17, plus the length of the portion 13, forming the lap. In applying the stay-strip to the second box the portion 13 is applied to the side of the box, so as to bring 75 the stay-strip *a'* into registration with the corner *A* of the box, when the covering-strip is wound upon the box, as already described.

The ends of the stay-strips may, if desired, 80 project beyond the edge of the covering-strip, as at 15^a, so that when the covering-strip and stay-strips have been applied to the box, as shown in Fig. 4, they may be turned over the edge of the box and attached to its inner side, 85 as indicated by the broken lines 18 and 19.

By my improved method of applying stay-strips to the corners of boxes very flexible material may be used, such as thin paper or thin cloth, which readily shapes itself to the form of the box-corner, and I secure a perfect adhesion of the stay-strip to the box independently of any irregularity in the surface simultaneously with the application of the covering-strip by means of hand-rubbing. In case of extremely-flexible stay-strips applied with their ends projecting beyond the end of the covering-strip I employ a rod or wire 20, placed parallel with the covering-strip and in the same plane as it passes through the covering-machine to afford a rest 90 or support for the projecting ends of the stay-strips.

95 What I claim as my invention, and desire to secure by Letters Patent, is—

The within-described method of attaching stay-strips to the corners of boxes, and consisting in attaching a series of stay-strips to one side of a strip of paper covering adapted to be wound around the outside of the box, with said stay-strips arranged at intervals 100 corresponding to the distances between the corners of the box; rendering the said covering-strip and the stay-strips attached thereto adhesive and winding the same around the outer surface of the box with the stay-strips 105 applied to the corners of the box, substantially as described.

Dated this 7th day of September, 1898.
THOMAS MORGAN.
